UNITED STATES PATENT OFFICE.

ALFRED K. ANCKER AND ROBERT F. MORTON, OF DENVER, COLORADO.

FLY SWATTER.

Application filed April 18, 1922. Serial No. 554,850.

To all whom it may concern:

Be it known that we, ALFRED K. ANCKER and ROBERT F. MORTON, citizens of the United States, residing at the city and county of Denver and State of Colorado, have invented certain new and useful Improvements in Fly Swatters; and we do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to an improvement in fly swatters, and has special reference to the handle thereof.

The ordinary house fly is a universal nuisance and one of man's most deadly foes and many different means have been devised for use in the extermination of this pest. Among the most popular weapons used in the killing of flies the ordinary "swatter" occupies a place in the front rank. The ordinary fly swatter has many specific embodiments but one well known form consists of a piece of wire cloth whose edges are covered by a strip of cloth and which is provided with a handle.

It is well known that flies when attacked by a swatter will seek a refuge on the wall near the ceiling or on the ceiling itself where they are out of reach.

It is the object of this invention to provide the ordinary swatter with an extensible handle by means of which the fly can be reached and killed in places where it would be safe from the ordinary short handled swatter. In order to more clearly describe our invention we shall have reference to the accompanying drawing in which—

Fig. 1 shows a top plan view of our swatter in semiextended position and

Fig. 2 shows the same with the handle fully extended.

Numeral 1 represents the woven wire swatter which has its edges enclosed in the folds of a cloth ribbon 2 while 3 represents the handle as a whole. The handle 3 consists of a piece of wire which is bent intermediate its ends to form a triangular portion 4 which engages the end of the swatter

which is held in place thereon by means of the corners 5 which are folded over as shown 55 and held in place by staples 6. The wire forming the triangular portion 4 is twisted together at 7 and then bent outwardly as indicated by numeral 8. The wires 9 are then extended substantially parallel for a 60 distance of 15 inches or more and are provided at their ends with eyelets 10 which engage the sides 11 of the other part of the handle. The two sides 11 are twisted together at a point 12 near their ends which 65 are then bent outwardly as indicated at 13 and are provided with eyelets 14 which engage the wires 9 in the manner shown. It is evident that the structure described and illustrated can be extended in the manner 70 shown in Fig. 2 or collapsed as shown in Fig. 1. In order to provide sufficient friction between the two and also to be frictionally held against relative movement when in extended or partially extended position eyelets 14 are spaced further apart than eyelets 10. When the handle is in the position shown in Fig. 2 the two parts are held against movement by a force which is due to the fact that the distance between eyelets 75 14 is greater than the normal distance between sides 11: this imparts to the eyelets 10 a tendency to move apart, which tendency is resisted by sides 11 causing the two parts of the handle to be held against relative 80 movement by a considerable force due to the friction developed between eyelets 10 and 14 and the sides 11 and 9.

Having now described our invention, what we claim as new is:

1. A handle adapted to be used with a fly swatter consisting of a wire bent intermediate its ends and formed into a closed loop adapted to co-operate with a flexible swatter element, the ends extending from said loop 95 portion in spaced substantially parallel relation and provided with eyelets which are adapted to engage the sides of a second elongated U-shaped handle member, the sides of which are twisted together near the ends 100 thereof, the ends being provided with eyelets engaging the sides of the first mentioned member.

2. A handle adapted to be used with a fly swatter consisting of a wire bent intermediate its ends and formed into a closed loop 105

adapted to co-operate with a flexible swat-
ter element the ends extending from said
loop portion in outwardly curved relation
and provided with eyelets which are adapted
5 to engage the sides of a second elongated
U-shaped handle member, the sides of
which are twisted together near the ends

thereof, the ends being provided with eyelets
engaging the sides of the first mentioned
member.

In testimony whereof we affix our signa-
tures.

ALFRED K. ANCKER.
ROBERT F. MORTON.
